UNITED STATES PATENT OFFICE.

ARON ZWEIBACH, OF BROOKLYN, NEW YORK.

DESIGN FOR A CHAIR-SEAT.

51,469.

Specification for Design.

Patented Nov. 6, 1917.

Application filed April 10, 1917. Serial No. 161,079. Term of patent 7 years.

To all whom it may concern:

Be it known that I, ARON ZWEIBACH, a citizen of the United States, residing at Brooklyn, in the county of Kings and State of New York, have invented a new, original, and ornamental Design for Chair-Seats, of which the following is a specification, reference being had to the accompanying drawing, forming part thereof.

Figure 1 is a perspective view of the chair seat.

Copies of this patent may be obtained for five cents each, by addressing the "Commissioner of Patents, Washington, D. C."

Fig. 2 is a longitudinal cross-sectional view thereof, and

Fig. 3 is a top plan view thereof.

I claim:—

The ornamental design for a chair seat as shown.

ARON ZWEIBACH.
